UNITED STATES PATENT OFFICE.

GEORGE H. LOBER, OF TOLEDO, OHIO.

AUTOMOBILE-RADIATOR.

1,313,492.

Specification of Letters Patent.

Patented Aug. 19, 1919.

Application filed November 7, 1917. Serial No. 200,705.

To all whom it may concern:

Be it known that I, GEORGE H. LOBER, a citizen of the United States, and a resident of Toledo, in the county of Lucas and State 5 of Ohio, have invented a certain new and useful Automobile-Radiator; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to automobile radiators and it has for its object to provide an efficient radiator that may be formed at a low cost and wherein the parts may be readily separated for purposes of repair, and 20 one wherein the deleterious effects of freezing will be entirely obviated.

The invention particularly has for its object to provide a radiator wherein not only water from the engine will be kept at a low 25 temperature, but also to provide a radiator wherein the water passageways are so formed that they will expand if the water freezes and thus prevent the ice from ripping the seams. It also has for its object to 30 provide a means for yieldingly resisting the expansion and causing the water passage-ways to return to their normal sizes or positions when the ice has melted. It also has for its object to provide a radiator 35 wherein water passage-ways are formed of strips having the same form and configuration and may be assembled to form not only the water passage-ways, but also air passage-ways. It also has for its object to not 40 only form the strips of the same form and configuration, but also to so form them that the air will be deflected in its movement through the radiator while cooling the water. The invention also has for its object 45 the production of other features and advantages that will appear from the following description.

The invention may be contained in radiators of different forms. I have selected one 50 of such constructions as an example and shall describe it hereinafter. The construction selected is illustrated in the accompanying drawings.

Figure 1 of the drawings is a front view 55 of the radiator containing my invention.

Fig. 2 is a front view of a portion of the core of the radiator. Fig. 3 is practically a full sized perspective view of a part of the core of the radiator.

1, Fig. 1, is the radiator containing my 60 invention having the usual water boxes in the upper and lower parts of the radiator body. 2 is the core of the radiator which is formed of a plurality of vertical strips that extend from the upper to the lower water 65 boxes of the radiator 1. The strips are corrugated longitudinal and so as to form semi-cylindrical corrugated parts 3 separated by flat parts 4. The strips are also provided with corrugated edges 5 that zigzag back 70 and forth along the front and rear edges of the strips. The strips being formed alike, they may be readily formed by running long strips from a coil between rollers that will form the longitudinal and edge corrugations and then the strips may be cut to the desired length.

Two sets of strips are used in the formation of the core of the radiator. The strips of one set are arranged in pairs and are 80 placed face to face so that the semi-cylindrical parts of the longitudinal corrugations will form tubular passage-ways extending between the pairs of strips, the tubular passage-ways being separated by 85 the flat portions of the longitudinal corrugations which in each pair abut one another. The zig-zag or angular corrugations of the edges of the pairs of strips fit into one another so as to form closed seams at opposite 90 edges of each pair of strips. The upper ends 6 of the pair of strips are turned over so as to extend at right angles to the tubular passage-ways that are thus formed. The ends 6 are of sufficient length so that they 95 will overlap the corresponding ends of successive pairs. When the edges of the strips are dipped in solder, the edges 5 are sealed. The ends of the strips are also dipped in solder and consequently are sealed. When 100 the strips are placed side by side and mounted to form the core of the radiator, the water passes through the tubular passage-ways 11 that are formed between the pairs of the strips. The strips being corrugated 105 longitudinally, when the water freezes in the passage-ways, will have ample room for expansion or bellying outward without pulling on the soldered and sealed edges. This prevents ripping along the corrugated edges. 110

One of the strips of each pair is provided with a strip 7 of elastic material which is transversely corrugated to form comparatively long spreading pressure parts. The 5 corrugations have flat contact portions 14 which press against the pairs of strips that are placed together to form the water passage-ways. The flat contact portions 14 slidably move along the pairs of strips when 10 the pairs of strips are placed together or when the walls of the pairs of strips expand by reason of the freezing of the water.

Each strip 7 is soldered at its center 8 to one of each pair of strips. When the pairs 15 of strips are placed together to form the core of the radiator, they are forced together so as to compress the parts of the elastic strip 7. The strips 7 by their pressure against the walls of the pairs of strips 9 and 20 10 operate to yieldingly maintain the abutting flat portions 4 in contact. When, however, the water freezes the expansion of the ice causes the water passage-ways to open and consequently force the center portion of 25 the strips 9 and 10 apart against the resistance of the spring parts formed in the elastic strip 7.

In order that the strips may be held in spaced relation and to give room for the 30 corrugations of the elastic strips 7, I have provided a second set of strips 19, formed in the same way as to longitudinal and edge corrugations as the strips of the first set described above. The second set of strips is 35 provided with large openings 15 through which the corrugation of the strips 7 may extend. The edges of each strip of the second set are so placed that the corners abut the corners of the edges of the pairs of strips 40 of the other set. This not only spaces the pairs of strips 9 and 10, but also gives the honey-combed appearance to the front and rear of the radiator. The longitudinal corrugations of the strips causes the air passing 45 through the openings formed by the abutting edges 5 to be deflected back and forth as it passes through the radiator to cool the pairs of strips having the water passage-ways. By this arrangement, the air is 50 brought into intimate contact with the walls of the water passage-ways and rapidly cools the water as it passes through the radiator.

When the strips have been assembled by placing the sets of strips alternately side by 55 side to form the water and air passage-ways, they may be bound together and the edges dipped in solder. Likewise, the ends of the core may be dipped in the solder so as to seal the overlapping ends of the pairs of the 60 strips that form the water passage-ways. The ends of the core thus formed are sealed in the water chambers of the radiators so as to direct the water, without leakage, into

the top of the water passage-ways and withdraw the water from the lower end of the 65 passage-ways.

I claim:

1. In a radiator, a plurality of pairs of strips having corrugations extending lengthwise of the strips and forming water passage-ways, spacing strips having corrugated edges located intermediate the pairs of strips and having a plurality of openings along their central portion, elastic means located between the pairs of strips for pressing the 75 walls of the pairs of strips and extending through the openings.

2. In a radiator, a plurality of pairs of strips having corrugations extending lengthwise of the strips and forming water passage-ways, elastic corrugated strips located intermediate the pairs of strips to force the strips of each pair together, the elastic strips secured at the centers to one side of each pair of strips, the corrugations of the elastic strip 80 being slidably movable along the pairs of strips.

3. In a radiator, a plurality of pairs of strips having longitudinal semi-cylindrical corrugations separated by flat portions and 90 edge corrugations placed to form cylindrical passage-ways, a plurality of strips having edge corrugations, the corners of the corrugations of the last named strips abutting the corners of the corrugations of pairs of 95 the strips to form transverse air passage-ways, the second named strips having large openings, a third set of corrugated strips located intermediate the pairs of strips, the corrugations of the third named set of strips 100 extending through the openings of the second named set of strips for yieldingly pressing against the first named set of strips.

4. In a radiator, a plurality of pairs of strips having corrugations extending lengthwise of the strips, said strips forming water passage-ways and edge corrugations, the edge corrugations of one strip setting into the edge corrugations of the other strip of each pair, strips located parallel to the water 105 passage-ways and having edge corrugations for spacing the pairs of strips, the corners of the edge corrugations of the pairs of strips abutting the corners of the edge corrugations of the spacing strips.

5. In a radiator, a plurality of pairs of strips forming water passage-ways, spacing strips having a plurality of openings along their central portions, elastic strips for pressing the walls of the pairs of strips and 120 located between the pairs of strips and having portions extended through the openings.

In testimony whereof, I have hereunto signed my name to this specification.

GEORGE H. LOBER.
